(No Model.)

H. THOMAS.

LOCKING AND RELEASING MECHANISM FOR CASH CARRIERS.

No. 379,618.

Patented Mar. 20, 1888.

Inventor.

Horatio Thomas.

By his Attorney
H. A. Chapman.

UNITED STATES PATENT OFFICE.

HORATIO THOMAS, OF CHICAGO, ILLINOIS, ASSIGNOR TO THE BOSTEDO PACKAGE AND CASH CARRIER COMPANY, OF ATLANTIC, IOWA.

LOCKING AND RELEASING MECHANISM FOR CASH-CARRIERS.

SPECIFICATION forming part of Letters Patent No. 379,618, dated March 20, 1888.

Application filed October 4, 1887. Serial No. 251,440. (No model.)

To all whom it may concern:

Be it known that I, HORATIO THOMAS, of Chicago, in the county of Cook and State of Illinois, have invented certain new and useful Improvements in Locking and Releasing Mechanism for Cash and Package Carriers; and I do hereby declare the following to be a full, clear, and exact description of the invention, such as will enable others skilled in the art to which it appertains to make and use the same.

My invention relates to an improvement in locking and releasing mechanism for the track-section of the elevator of a cash and package carrier, and is particularly designed to be employed in connection with the cash and package carrying apparatus forming the subject of Patent No. 367,951, granted to Bostedo and Thomas.

The apparatus above mentioned is of a type known as a "two-track" apparatus, the essential features of which are as follows:

Two tracks are employed whereon to transmit cash or packages from a clerk's station to a cashier's stand or a bundle-table and return the change or bundles to the starting point or clerk's station.

The tracks whereon the transport-cars are run are placed in the same vertical plane, the upper track being, preferably, employed to dispatch the unwrapped goods or cash received therefor by a clerk to the bundle-man at his table or the cashier's stand, the lower track being employed exclusively to return the wrapped bundles or change from these localities to the clerk's station.

The preferred form of cars employed on the two tracks mentioned are furnished with two wheels grooved to run on the edges of the tracks, and a car that runs on the upper track is also employed on the lower track, a suitable elevator being provided—one at each clerk's station—to permit the elevation or lowering of the car from one track to the other, and also to facilitate the lowering of the car from the return or lower track to the hand of the clerk or other operator at such a station.

In the construction of the elevators a skeleton frame is used that is adapted to slide on upright guides, and to this frame a track-section is attached that receives a car on it and

returns this car secured to permit it to be lowered or raised, as the case may be.

The track-section that is secured to the elevator is provided with a mechanism to check momentum of an approaching loaded car and store this energy to dispatch a car on the upper track when the car is raised to line with this track. A further provision is to cause the track-section of the elevator, and in consequence the elevator, also, to be released from an aligned position with the lower track by the impact of the car that runs onto the elevator when it comes from a cashier's stand or a bundle-table, this automatic release being simultaneous with the locking of the car securely on the elevator track-section, so as to insure its safe descent to the hand of the clerk or other receiver without his assistance or observation of the operation.

The nature and object of my present invention are to improve upon the devices previously employed to lock and unlock an elevator track-section, to render it more perfect in operation as a releasing device, and, further, to cause the lock which retains the elevator track-section in secured adjustment with the lower track to automatically lock the track-supporting bolts in extended position to engage the lower track and hold the elevator in a line with it when the momentum previously stored in a spring connected to this mechanism is released and utilized to start a car on the upper track.

With these objects in view my invention consists in certain features of construction and combinations of parts, that will be hereinafter described, and pointed out in the claims.

Referring to the drawings making a part of this specification, Figure 1 is a rear side elevation of an elevator track-section bar with my improved elevator locking and releasing mechanism shown in a locked position. Fig. 2 is a rear side elevation of an elevator track-section bar with the improved locking and releasing device in a position to release the elevator and permit its descent from a lower track to the hand of a receiver or clerk. Fig. 3 is a front elevation of an elevator track-section bar, showing the car arresting and locking mechanism connected with my novel ele-

vator locking and releasing device located on the rear surface of the elevator track section bar. Fig. 4 is a cross-section of the elevator track-section bar, taken on the line $x-x$, Fig. 5 1, to show the manner in which the car-arresting device is attached to the elevator locking and releasing mechanism.

As it is essential to the proper operation of the elevator locking and releasing device 10 which is the subject of the present invention that it be combined with an efficient car arresting and retaining apparatus that will act in conjunction therewith, I have arranged this novel locking and releasing appliance to be operated on the same elevator track-section bar in connection with the car arresting and dispatching apparatus disclosed in the patent previously referred to, a description of which will now be given, in order to show its 15 manner of conjunctive operation with the device which is the subject of the present application for patent.

A A are the ends of a lower track at a clerk's station, and B the elevator track-section bar 25 in locked engagement with these track ends.

The body of the track-section bar B is recessed on its front face to receive the car arresting and dispatching apparatus above alluded to. This device, as has been intimated 30 previously, serves to arrest a car on the elevator track-section and store the energy of its impact, to be afterward utilized in starting a car that is elevated to the upper track, this impetus being given when the elevator track-section is made to line with the upper track, and thus force the car on this upper track to speed toward the cashier's stand or the bundle-table. A slot, i, is made through the bar B parallel to the top and bottom edges of this bar, 35 as well as the shoulders formed by the recess or excavation made in the face of the bar. The slot i is of proper length to permit free action of the working parts that have connection with it, as will be explained.

40 A ratchet-bar, C, is placed in the recess cut in the track-section bar B, and is of such proportionate width to this recess as to slide freely in it.

Integral with the bar C the portion D is extended at one end. It is cut with ratchet-teeth on its top edge, these teeth having their sloping edges 1 and square shoulders 2 so arranged that an engaging-dog will lock the bar C as it is slid endwise, as will be further explained. The guide-plate D' is so attached to the bar C that it will serve to hold in place and permit the vertical sliding movement of the engaged ends of the latches E F. (See Fig. 3.)

45 The latch E is pivoted at E' to the ratchet-bar C, and its free end is held by a loosely-bearing overhanging flange, e, to slide vertically a short distance, its upward movement being limited by the abutment of its top edge with the shoulder or recessed edge e' of the bar B. Near the pivot E' of the latch E a spring, E², is made to bear on the upper edge 50 of the latch and cause it to rest normally, with

the latch-toe d projecting below the lower edge of the bar B to engage a stud that projects from the side of the frame of a car when the 70 car is run onto the elevator, of which the bar B is an attached part. The latch F is also pivoted to the ratchet-bar C at e, and rests with its sloped edge against a shoulder, e', formed on the projecting lower flange, e³, produced by 75 recessing the track-section bar B; and it may here be explained that when this bar is slid endwise this movement will automatically raise the latch. If the bar moves toward the end on which the ratchet-teeth are cut, a movement 80 in an opposite direction will permit the latch F to be depressed and project its latch-toe d' below the edge of the bar B, this depression being accomplished by the spring f, which is affixed to the latch F near its pivoted end, the 85 opposite end of this spring having an engagement with the side of the bar B at f'. (See Fig. 3.)

When a car runs onto the elevator track-section bar B and passes the latch-toe d' of the 90 latch F, it comes into contact with the latch-toe d of the latch E and slides the ratchet-bar C endwise. This movement will be cushioned by a spiral spring, g, supported on a slide-rod, g', which has a sliding support in the perforated block h, fixed to the bar B, and against which the spiral spring g bears.

The compression of the spiral spring g by the collision of a car with the shoulder of the latch-toe d will permit the latch F to fall into 100 place behind the stud formed on the car-frame that has engagement with the shoulder of the latch-toe d of latch E. In this manner a car is located in place on the elevator track-section bar B between the adjacent shoulders of 10; the two latches E F, and is thus held until released by another operation.

Upon the track-section bar B, above the portion D of the ratchet-bar C, an arm, G, is pivoted at 3 to engage the ratchet-teeth cut in this 110 extended portion D, the inner end, 4, of this arm having a depending toe, 5, formed on it to fit the ratchet-teeth and lock with them, a spring, 6, affixed to the top edge and having contact with the overhanging edge of the bar 115 B, causing a proper depression of the arm G to lock its toe 5 with the teeth of the bar D when this bar D and its attached portion C is moved endwise by an abutment of a car, as has been explained.

The outer end, 7, of the pivoted arm G is 120 extended clear of the end track-section bar, B, and is made to strike a projecting pin on the side of the upper track when the elevator is raised to line with it. When such a contact of parts is made, the lever will be vibrated, its toe released from the teeth of the ratchet-bar, and this bar is quickly projected endwise by its attached spiral spring g to give a car a starting impulse, and it will be apparent that 130 the sliding of the bar C will raise the latch F, and thus permit the progressive movement of the car.

The foregoing description has been given to

render plain the operation of the locking and releasing mechanism which is the subject of my present invention. This device is located upon the reverse side of the track-section B', and is shown in Figs. 1 and 2. Upon the face of the bar B two flat elongated locking-bolts, I J, are held in sliding contact therewith by their ends. These bolts are similar in form and manner of attachment; hence a description of the sliding locking-bolt I will answer for both. The bolt I has its outer end, I', cut to form a hook, m, that engages cylindrical studs m', which project from the front faces of the permanent lower track at each side of the opening in it at a station near its ends. The lower end, I', is enlarged in width, having its upper edge sloped or cut on an incline, s, to afford a proper form for contact with the stud m' when the track-section bar B is raised from the counter at a station to line with the lower track, and it should be stated that the construction is similar at each end of the bar B as regards the locking-bolts I J and the studs m' that are placed to support the bar level with the track-line. The enlarged end I' is provided with a triangular hole, I'', cut through it near the hook m. The inclined side m' of the triangular orifice I'' is sloped upwardly and inwardly to be engaged by the fixed stud m', which projects from the track-section B in proper relative position to be in contact with the side m', as stated, when actuated by means that will be described in its proper connection. The stud m' is provided with a flanged head to bear loosely on the outer surface of the locking-bolt I and prevent its lateral displacement. Near the inner or opposite end of the locking-bolt I a short longitudinal slot, n, is cut through the body of the bolt to receive and have a sliding engagement with a flanged and shouldered screw-bolt, n', which latter holds the bolt I in proper position on the side of the bar B.

It is evident that a weight or pressure applied to the top surface of the bar B when the hooked ends of the locking-bolts I J are resting upon the studs m' will cause the outer ends of the bolts I J to move upwardly and slide inwardly by reason of the engagement of the inclines m' with the studs m'. It is also apparent that the inward sliding of the bolts I J will instantly release the track-section to lower a car on it to the counter, if the bolts are not prevented from sliding inwardly, as just described.

I will now explain the construction of other parts that constitute the lock for the bolts I J.

The length of the two locking-bolts just mentioned is such in relation to the length of the bar B, to which they are attached, that a considerable space intervenes between their inner ends, upon which the offset portions M M' are integrally formed to afford a space on the bolt I for the pivotal attachment of the latch-bar K, the corresponding offset on the inner end of the bolt J allowing the free beveled end of the latch-bar to fall into place by gravity and

engage the inclined shoulder n, formed on this end of the bolt J to receive it.

The length of the latch-bar K is such in relation to the space between the inner ends of the locking-bolts I J that it will drop into place and form a spreading latch-bar to lock the bolts rigidly when they are forced outwardly as far as the studs m' will permit them to move. The inner ends of the locking-bolts I J are further provided with ears o o', which project from their free outside surface at the ends of the bolts. These ears o o' are each perforated in a line parallel with the lower edge of the bar B to receive the spring supporting rod O, on which the spiral spring O' is placed. Near one end of the rod O a collar, O'', is rigidly secured on its body, a sufficient portion of the rod projecting beyond the collar O'' to enter the perforation in the ear o on bar I, the collar resting against the adjacent surface of the ear. The opposite end of the rod O enters the perforation in ear o' on the bar J, so that the spiral spring O', which is located between the rigid collar O'' and the ear o', will exert its expansive force to push the locking-bolts I J endwise and hold them in such projected adjustment.

The length of the slot i, that is made through the bar B, is such that it will extend from the inner end of one locking-bolt to the inner end of the other bolt, and the stud S, that projects from the rear surface of the ratchet-bar C through this slot, is adapted to bear upon the upper edge of the latch-bar K, near its free end K', to hold the bar depressed and cause a rigid lock of the bolts I J when they are projected by the spring O' and the latch-bar has dropped into place between them, as shown in Fig. 1. The latch-bar K is cut away on its upper edge between the points K' K'', to reduce the width of said bar, and thus allow it to be sufficiently elevated to cause its free end to rise above the inner end of the sliding bolt J before the upper edge of the bar is in contact with the stud S. This elevation of the latch-bar is caused when a car is being elevated to allow it to pass through the gap in the lower track to line the track-section bar B with the upper track and dispatch a car, it being understood that the spiral spring g, which cushions the recoil of the car and stores its momentum, has been previously compressed by a car that was sent from a cashier's stand or bundle-table to this station, the longitudinal movement of the ratchet-bar C thus effected carrying the stud S toward the center of the latch-bar K on the rear side of the track-section bar B and permitting the engagement of the inclined edges s of the ends of the locking-bolts I J with the fixed studs m' to push these bolts inwardly, as the sloped free end of the latch-bar K, which corresponds with a similar inclined shoulder, n, against which it rests, will adapt it to rise when the contact of the bolts with the studs m' takes place, as described.

When a car is to be dispatched, it is raised, as just stated, and when the section bar B is about in line with the ends of the upper track the arm G will collide with a stud affixed to 5 project from an adjacent end of this track and by this contact release the ratchet-bar C. The spring g, that is attached to the bar C, will project it in a proper direction to carry the affixed stud S over the high portion K² of the 10 edge of the latch-bar K and hold it depressed to securely retain the locking-bolts I J in extended adjustment and adapt them to support with their hooked ends the elevator and attached track-section bar B in line with the lower track, where it will remain until a car with 15 a package-receptacle attached arrives at this station, runs onto the elevator, compresses the spring g, and slides the ratchet-bar C. The movement just described will unlock the latch-bar K and allow the weight of the car and attached package-receptacle to push the locking-bolts I J inwardly, in consequence of which a release of the hooks m from the supporting studs m' will be afforded, and the elevator, 20 with its load, will be lowered to the counter to allow the clerk to readily have access to the same and secure the bundle or change that was transmitted from the other end of the line.

The elevator locking and releasing mechanism herein shown is not exclusively confined 30 in its use to the Bostedo and Thomas apparatus of two-track cash and package carriers, as it is capable of being adapted to use on any two-track system where one track is located 35 above the other in the same vertical plane. I do not, therefore, limit its use to the system to which it is herein applied.

Many slight changes might be made in the construction of the device without a departure 40 from its spirit and scope. I do not, therefore, wish to limit myself to the exact form shown; but,

Having fully described my invention, what I claim as new, and desire to secure by Letters 45 Patent, is—

1. The combination, with a track-section bar, of two locking-bolts adapted to slide endwise on the track-section bar, and a latch-bar adapted to fall between and engage the inner 50 ends of the bolts when the latter are extended and lock them in position, substantially as set forth.

2. The combination, with a track-section bar, of two locking-bolts adapted to slide endwise, a latch-bar adapted to fall between and engage the inner ends of the bolts when the latter are extended and lock them in position, and a sliding ratchet-bar carrying a pin for holding the latch between the bolts.

3. The combination, with a track-section bar and car arresting and dispatching apparatus for stopping and starting a car, of sliding locking-bolts and a latch-bar adapted to fall between the inner ends of said bolts and 60 lock them in their extended position, substantially as set forth.

4. The combination, with a track-section

bar and a car arresting and dispatching apparatus thereon for stopping and starting a car, of two sliding locking-bolts, a latch-bar adapted 70 to fall between the inner ends of the bolts and lock them in their extended position, and the ratchet-bar of said apparatus carrying a pin adapted to engage the latch-bar, whereby the position of the latter is regulated and controlled by the movements of the arresting and dispatching apparatus, substantially as set forth.

5. The combination, with a track-section bar having a slot therein, and a car arresting 80 and dispatching apparatus for stopping and starting the car, the ratchet-bar of said apparatus carrying a pin, which latter passes through the slot in the track-section bar, of two sliding locking-bolts, a latch-bar adapted 85 to fall between the inner ends of said bolts and lock them in their extended position, the said latch-bar being held in locked position between the bolt and pin, substantially as set forth.

6. The combination, with a track-section 90 bar and a car arresting and dispatching apparatus for stopping and starting a car, the ratchet-bar of said apparatus having a pin or projection thereon, of two sliding locking-bolts, a spring for forcing the bolts apart, and 95 a latch bar adapted to fall between the inner ends of the bolts and lock them in their extended position, the said latch-bar being held in locked position between the bolts by the pin or projection on the car arresting and dispatching apparatus, substantially as set forth.

7. The combination, with the track-section bar, of sliding locking-bolts, and a latch-bar pivoted to one of said bolts and adapted to fall 100 between the inner ends of said bolts when the latter are extended and lock them in position.

8. The combination, with a track-section bar, of two locking-bolts having a sliding connection with this bar and adapted to unlock by a simultaneous upward and inward movement of their outer ends, and a latch adapted 110 to fall between the inner ends of said bolts and lock them in position, substantially as set forth.

9. The combination, with a track-section 115 bar and two locking-bolts held to slide in opposite directions endwise on this bar, of a pivoted latch-bar that holds the bolts locked in extended adjustment, a spiral spring to force the bolts apart, and a car provided with a stud 120 that is adapted to release the latch-bar from locked contact with the locking-bolts when a car runs onto the elevator track-section, substantially as set forth.

10. The combination, with a track-section 125 bar, two sliding locking-bolts that are made to move toward each other when they unlock this bar, and a spiral spring supported on a rod, so as to bear on the inner ends of the locking-bolts, of a latch-bar pivoted to one end of one 130 of the locking-bolts and adapted to lock both bolts when extended, when said latch-bar is held by a stud on the ratchet-bar, substantially as set forth.

11. The combination, with a track-section bar, two sliding locking-bolts that have their outer ends connected to the track-section bar to slide inwardly and raise upwardly a limited
5 distance in the act of releasing the bar on which they are secured, and a spiral spring mounted on a rod, the spring bearing on the inner end of each locking-bolt, of a latch-bar pivoted by one end to a locking-bolt and en-
10 gaging the other bolt, and a stud that projects through a slot in the track-section bar and is attached to a car-arresting device to move end-

wise and release the latch-bar and unlock the track-section bar when a car is arrested on this track-section bar in line with the lower 15 track, substantially as set forth.

In testimony whereof I have signed this specification in the presence of two subscribing witnesses.

HORATIO THOMAS.
